CARRYING CASE FOR SUCTION CLEANERS
OF THE HORIZONTAL TANK TYPE

Ethel Morrison Smith, Haddonfield, N. J.

Application July 12, 1946, Serial No. 683,019

2 Claims. (Cl. 150—52)

1

This invention relates to carrying cases and more particularly to handbags of the type which are designed for carrying portable vacuum cleaners, together with all the tools and attachments adapted to be used therewith.

Handbags of this type have recently attained great popularity because of their light, sturdy construction, and they are used extensively for carrying all sorts of articles. Because of their relatively small size, however, it has been impossible to enclose some articles such as vacuum cleaners which it is frequently desirable to carry from place to place.

It is an object of the present invention to so construct a handbag that articles such as vacuum cleaners together with all the tools and attachments adapted to be used therewith may be conveniently carried therein.

Other objects and advantages of the invention will appear hereinafter.

A preferred embodiment of the invention selected for purposes of illustration is shown in the accompanying drawings, in which—

Fig. 1 is a side elevation of a carrying case constructed according to the present invention;

Fig. 2 is a top plan view thereof;

Fig. 3 is a vertical longitudinal section taken along the line 3—3 of Fig. 2;

Fig. 4 is a vertical longitudinal section taken along the line 4—4 of Fig. 2;

Fig. 5 is a horizontal section; and

Fig. 6 is an enlarged transverse section taken along the line 6—6 of Fig. 4.

In the preferred embodiment illustrated the carrying case 10 comprises a bottom member 11, side members 12 and 13, and top sections 14 and 15.

Preferably the carrying case is formed of canvas or like flexible material, the bottom member 11 being formed of a single piece of material which is substantially rectangular in outline, as shown in Fig. 5. Each side member 12, 13, is likewise formed of a single piece of material having the outline shown in Fig. 1. The top sections 14 and 15 are formed of strips of material of suitable length and breadth, said strips of material having substantially parallel longitudinal edges, as shown in Fig. 2.

One longitudinal edge 16 of the side member 12 is connected to one longitudinal edge 17 of the bottom member 11, by stitches 18 (Figs. 1 and 6), and similarly one longitudinal edge 19 of the side member 13 is stitched to the other longitudinal edge 20 of the bottom member 11, as indicated at 21, Fig. 6. One longitudinal edge 22 of the top section 14 is stitched to the adjacent edge 23 of the side member 12, as indicated at 24, Figs. 1, 2, 5 and 6, and one longitudinal edge 25 of the top section 15 is connected to the adjacent edge 26 of the side member 13, by stitches 27.

2

Preferably the several parts of the carrying case 10 are connected by upholsterer's seams as shown, since such construction enhances the appearance of the finished article. The ends 28 and 29 of the top sections 14 and 15 are connected to the ends 30 and 31 of the bottom member 11 by stitches 32, 33, to provide plain seams at the junction of the top sections with the bottom member 11 at each end of the case, as shown in Figs. 3 and 4.

The longitudinal edge 35 of the top section 14 and the longitudinal edge 36 of the top section 15 are respectively supplied with intermeshing parts 37, 38 of a slide fastener which serves as a closure member for the carrying case (Figs. 5 and 6). The intermeshing parts 37, 38 of the slide fastener extend substantially the entire length of the top sections 14, 15, and at each end the parts are reinforced by patches 39 and 40 which are stitched thereto as indicated at 41, 42, in Figs. 2 and 5.

The arrangement is such that when the parts 37 and 38 of the slide fastener are unmeshed, the top sections 14 and 15 and the sides 12 and 13 can be spread apart to provide an elongated opening in the case, said opening extending substantially the full length of the bottom 11.

Preferably the bottom 11 has an area of a size to receive and support a portable vacuum cleaner of the horizontal tank type as indicated by broken line 45 in Figs. 4 and 5.

In the closed position of the case, the top sections 14 and 15 are adapted to have their marginal portions having the slide fastener parts 37, 38 in continuous edge to edge abutment along the longitudinal center of the carrying case, said top sections being continuously interconnected by the intermeshing parts 37, 38 of the slide fastener.

Due to the manner in which the top sections 14 and 15 are arranged with the side members 12 and 13 and with the bottom member 11, said top sections also provide end walls 47 and 48 (Figs. 3 and 4) for closing the ends of the carrying case.

As shown in Figs. 5 and 6, the side member 13 is provided with pockets 50 and 51 on the inside thereof adjacent to the junction of the side member with the bottom member 11. The pockets 50 and 51 may be, if so desired, formed of a single piece of canvas 52, of the same type of material used in constructing the main body of the carrying case. One longitudinal edge 53 of the material 52 can be inserted in the seam between the bottom member 11 and the side member 13 so that it is connected to said members by the stitches 21, Fig. 6. The pockets 50 and 51 are formed by vertical rows of stitches 54, 55 and 56, whereby both pockets will be open at the top and pocket 51 will be considerably larger than pocket 50. Pocket 50 is designed to contain the dusting brush attachment (not shown) used with the

vacuum cleaner, and pocket 51 is designed to contain other attachments used with the vacuum cleaner, such as the mop attachment and the rug cleaner attachment (not shown).

As shown in Figs. 4 and 6, the side member 12 is provided on the inside thereof with a pair of double loops 57, 58 and 59, 60 which are adapted to receive a pair of extension tubes used with the vacuum cleaner (not shown).

Also mounted on the inside of the side member 12 adjacent the end 47 and beneath the loop 58, is a pair of single loops 61, 62 which are spaced apart a suitable distance so as to provide a support for a radiator cleaner or similar attachment (not shown).

Near the opposite end 48, the side member 12 has a single loop 63 fixed to the inside thereof for supporting a furniture attachment or similar device (not shown).

A single length of flexible material 66, arranged in the form of a loop to provide a pair of handles 67 and 68, is connected to the exterior of the side and bottom members of the carrying case by stitches 69. The handle 67 extends upwardly above the side member 12 and the handle 68 extends upwardly above the side member 13. Both handles can be arranged to overlie the top of the carrying case in the manner shown in Fig. 2 to provide convenient members to be gripped by the hand of a person when it is desired to transport the carrying case. The stitches 69 may also be of continuous loop form and the adjoining ends of the material 66 can be cross stitched to the bottom member 11, as indicated at 10, Fig. 5.

The side member 12 has one end of a strap 71 of flexible material secured thereto, as indicated at 72, Fig. 1, and the side member 13 has a buckle 73 secured thereto, as indicated at 74, Fig. 3. The strap 71 and the buckle 73 are arranged substantially at the mid point of the length of the carrying case and centrally between the loops constituting the handles 67, 68, the buckle 73 being adapted to receive and retain the strap in well known manner. A length of vacuum cleaner hose (not shown) may be inserted under the strap 71 and carried on top of the case 10.

It will be seen that I have produced a handy carrying case for vacuum cleaners and the like which can be carried from place to place and at the same time keep all equipment together in an accessible manner.

Having thus described my invention what I claim and desire to secure by Letters Patent is:

1. A carrying case for suction cleaners of the horizontal tank type formed of canvas or the like flexible material, comprising a flat bottom having longitudinally extending substantially parallel side edges and end edges arranged substantially at right angles to said side edges, side members, each side member having a longitudinal edge connected to a longitudinal side edge of the bottom by stitches, each said side member having an end edge at each end and a top edge, said end edges and said top edge of each side member forming a continuous edge portion wherein the top edge is arranged substantially in parallel relationship with respect to the longitudinal side edge of said bottom and the end edges are inclined toward each other outwardly from the connection of the side member with the bottom, a pair of inwardly directed top and end members, each formed of an elongated substantially rectangular piece of material having an opposed pair of longitudinal side edges and an edge at each end arranged sub-

stantially at right angles thereto, each of said top and end members having a longitudinal side edge connected to the end edges and top edge of a side member by stitches and its end edges connected to the end edges at each end of said bottom by stitches, whereby said top and end members have longitudinal meeting edges extending from a point adjacent one end of said bottom to a point adjacent the other end of the bottom, and means on the longitudinal meeting edges of said top and end members for detachably securing together the meeting edges of said top and end members.

2. A carrying case for suction cleaners of the horizontal tank type, said case being formed of canvas or the like flexible material, comprising a flat bottom having longitudinally extending substantially parallel side edges and end edges arranged substantially at right angles to said side edges, opposed side members, each side member having a longitudinal edge connected to a side edge of the bottom by stitches, each said side member having an end edge at each end and a top edge, said end edges and said top edge of each side member forming a continuous edge wherein the top edge is arranged substantially in parallel relationship with respect to the longitudinal side edge of said bottom and the end edges are inclined toward each other outwardly from the connection of the side member with the bottom, a pair of inwardly directed top and end members, each formed of an elongated substantially rectangular piece of material having an opposed pair of longitudinal side edges and an edge at each end arranged substantially at right angles thereto, each said top and end member having a longitudinal side edge connected to the end edges and top edge of a side member by stitches and its end edges connected to the edges at each end of the bottom by stitches, whereby said top and end members have longitudinal meeting edges extending substantially from a point adjacent one end of said bottom to a point substantially adjacent the other end of the bottom, a plurality of pockets formed on the inside of one of the side members, a series of loop straps formed on the inside of the other side member, a suction cleaner and various tools and attachments used therewith being adapted to be positioned within the case with the suction cleaner supported by the bottom and the tools and attachments disposed in the pockets and the loop straps, whereby the top, ends, and the sides of the case can be spread apart to expose substantially the whole of the bottom so that the interior of the case is accessible for the purpose of removing the contents thereof and for placing articles therein, and means on the longitudinal meeting side edges of said top and end members for detachably securing together the meeting edges of said top and end members.

ETHEL MORRISON SMITH.
